UNITED STATES PATENT OFFICE.

FRANK E. MARCY, OF SALT LAKE CITY, UTAH.

MECHANICAL CLASSIFIER.

1,306,188.

Specification of Letters Patent. Patented June 10, 1919.

Application filed May 25, 1918. Serial No. 236,488.

To all whom it may concern:

Be it known that I, FRANK E. MARCY, a citizen of the United States, residing at Salt Lake City, in the county of Salt Lake and State of Utah, have invented certain new and useful Improvements in Mechanical Classifiers, of which the following is a full, clear, and exact description, reference being had to the accompanying drawings, forming

10 a part hereof.

The present invention is directed to improvements in what are known in ore dressing as mechanical classifiers in contradistinction to the purely hydraulic type of machine in which the agitation is effected by an upward current of clean water through which the coarse or heavy particles of the material under treatment are caused to fall, and by which the fine particles or fines are 20 separated from the coarser particles or sands. The classifier under consideration may be used in circuit with ore grinding mills, serving the specific purpose of returning the coarse sands which form a component part of the finished product of the mill, back to the mill for further grinding. The object sought of course is to effect a separation between the coarse sands and fines without the use of screens, the latter being impractical for sizes finer than 40 mesh. So far as concerns the immediate improvement herein, one of the objects sought is to provide a 30 classifier which will remove a maximum or any desired quantity or character of fines and prevent their return to the mill with the coarser sands requiring further treatment or regrinding. A further object is to provide means for varying the character of agitation imparted to the pulp, producing at pleasure 40 an upward or downward current, or mere agitation, and thereby effectively controlling the classification of the material. A further object is to provide means for feeding the pulp to the classifier below the surface of the 45 pool or plane of overflow to prevent any coarse sands from floating away, the fine material being however free to rise through the pulp to the surface and pass off with the overflow. A further object is to prevent the 50 fine sands from taking a direction away from the overflow (or toward the conveyer), the tendency of the fines to take the wrong direction in this type of machine being due to the circulation set up by the conveyer 55 plowing through the pulp. A further ob-

ject is to provide a classifier which will treat a maximum quantity of material in a minimum amount of time; one which is simple in construction and containing a minimum number of parts; and one possessing further 60 and other advantages better apparent from the following detailed description in connection with the accompanying drawings in which—

Figure 1 represents a side elevation of my 65 improved classifier; Fig. 2 is a top plan thereof with feed hopper omitted; Fig. 3 is a vertical cross-section on the zig-zag line 3—3 of Fig. 2; Fig. 4 is a rear end elevation; Fig. 5 is an end view of the tail pulley or 70 drum of the belt conveyer; Fig. 6 is an elevation of the lower end of the stirrer shaft showing the stirring blades set at an angle to the plane of rotation thereof; Fig. 7 is a 75 vertical longitudinal sectional detail on the zig-zag line 7—7 of Fig. 2; and Fig. 8 is an elevation of the lower end of the stirrer shaft showing the stirring blades set parallel to the plane of rotation thereof.

Referring to the drawings, 1, represents 80 an oblong tank terminating at one (the lower) end in a relatively deep portion forming a sorting basin or compartment C, and in a relatively shallow portion or extension D at the opposite (or upper) end, the 85 level of the pulp or water line in the deep portion being indicated by the dotted line α in Fig. 1. The maximum depth of the pulp in the sorting compartment will of course depend on the inclination or pitch of the 90 inclined bottom α of the tank, the plane of overflow from said compartment being along the upper edge of the vertical terminal wall b of the tank. The overflow from the sorting compartment is caught in a launder 2 by 95 which it is conducted to any suitable point for further treatment and the recovery of the fines. Operating within the sorting compartment C on each side of the medial longitudinal line or axis of the tank 1 is a 100 vertically disposed stirrer shaft 3, the shafts being supported by the timbers T as shown or in any other suitable mechanical manner. The stirrer shafts are operated from a transverse shaft 4 disposed across the tops of the 105 timbers T, the said shaft having rotation imparted thereto by means of a belt B leading from the adjacent end of a parallel drive-shaft 5 supported in suitable bearing blocks 6 at the upper end of the shallow portion D of 110

the tank. The shafts 4 and 5 are provided with step pulleys P and P' respectively over which the belt B passes, and by means of which the speeds of the shafts may be regulated. The opposite end of the shaft 5 terminates in a pinion 7 which meshes with a gear wheel 8 at the adjacent end of the drum shaft 9 likewise mounted in the blocks 6, said shaft 9 carrying the upper drum 10 over which passes the endless conveyer belt 11, the lower end of the belt passing over the crown tail pulley or drum 12 mounted on the shaft 12'. The shaft 4 is provided with two bevel pinions 13 meshing with corresponding pinions 14 at the upper ends of the stirrer shafts, the pinions 13 engaging the pinions 14 of the respective shafts on opposite sides whereby the shaft 4 imparts to the stirrer shafts 3 simultaneous rotation 20 in opposite directions (see arrows Fig. 2). The lower end of each stirrer shaft terminates in a square hub or enlargement 15, opposite each face of which is screwed a blade or agitator 16, the blade being held against rotation by a set-screw 17 carried by the hub and driven firmly against the screw stem 18 of the blade (Fig. 6). The blades being rotatable about the axes of the screw stems 18 may be adjusted to any angle or pitch relative to the (horizontal) plane of rotation of the stirrer shaft, as shown in Figs. 6 and 8. In Fig. 6 the blades are set at an angle to the rotation plane; and in Fig. 8 they are set parallel thereto. They may be set to any angle between the horizontal and vertical positions as clearly obvious from the drawings. The shaft 5 has rotation imparted thereto from the belt pulley 19, a loose pulley 19' being mounted adjacent to the tight pulley 19 as well understood in the art.

The outer face of the belt conveyer 11 is provided with a series of transversely disposed angle bars 20 which are slightly bowed or arched outwardly (Fig. 4) to conform 45 to the crowned peripheries of the drums 10 and 12. The legs of the angle bars projecting from the belt form rakes or scrapers whose free edges travel in proximity to the outer sweep of the blades 16 and operate 50 close to the upper surface of the inclined bottom *a* of the tank, thereby carrying the sands from the sorting compartment to the upper end of the tank where the sands discharge into the inclined launder 21 whence 55 they are conducted to the mill for regrinding. As shown in the drawings, the bars 20 extend beyond each side of the belt 11, the center of the belt being disposed along the medial longitudinal axis of the tank. To 60 impose proper tension on the belt the bearings or blocks 6 supporting the drum shaft 5 (and shaft 9) are made adjustable as well understood in the art.

It was pointed out above that in classifiers 65 of the type under consideration the fine ma-

terial has a tendency to flow over in the direction of the conveyer as indicated by the dotted arrow in Fig. 1, whereas it should flow toward the overflow edge *e* of the wall *b*. In the present embodiment of my invention this tendency of the fines to flow in the wrong direction (toward the conveyer) is overcome or arrested by the side aprons 22, these being in the form of sheet metal strips supported on angle brackets 23 secured to the sides of the deep portion of the tank, said aprons being disposed at an incline corresponding to the pitch of the upper lap of the belt conveyer 11, the lower portions of the aprons describing substantially a semi-circle (Fig. 7) conformable to the curvature of the periphery of the tail drum 12, and terminating below the center line of said drum. The upper ends of the aprons extend above the pulp line *x*, the inner longitudinal edges thereof being spaced sufficiently from the adjacent or side edges of the conveyer belt to prevent rubbing against the belt. The aprons are moreover disposed slightly below the plane of travel of the upper lap of the conveyer belt, whereby the projecting terminals of the bars or scrapers 20 clear the upper faces of the aprons. The aprons while preferably made of sheet material may be constructed in any way appealing to the skilled mechanic. The aprons are in the nature of shelves or diaphragms between which the lower portion of the upper lap of the belt is free to travel; and while herein shown as secured to the side walls of the tank, they may be secured in any other suitable mechanical manner.

To prevent any coarse sands from floating away by way of the overflow from the sorting compartment, I mount across the tank a feed box or hopper 24 the discharge mouth 24' of which extends below the pulp line *x*, the pulp being discharged from the hopper preferably at a point between the stirrer shafts 3 and the tail drum 12. By introducing the feed below the surface of the pool, or pulp line *x*, the fine particles are permitted to rise up through the pulp and be discharged by way of the overflow, the coarse sands remaining behind. Were the pulp discharged on top of the pool, some of the coarse sands would float away and become mixed with the fines thereby resulting in imperfect classification. The separation of the fines from the coarse sands is thus enhanced by discharging the pulp into the compartment C below the surface of the pool.

The operation is substantially as follows: The pulp (water mixed with the crushed ore or other material) is delivered to the hopper 24 from any suitable source, the hopper discharging the material at a convenient point beneath the surface of the pool or pulp line *x* so that none of the coarse sands can float

away over the edge *e* (Fig. 1). Rotation being imparted to the shaft 5 clockwise (see arrow in Fig. 1) the pinion 7 on said shaft will impart a counterclockwise rotation to 5 the gear wheel 8 and to the drum 10 carried by the shaft 9, thereby imparting a corresponding movement to the belt conveyer 11 as shown by the arrows in Fig. 1. Through the instrumentality of the belt B, 10 rotation will be imparted to the shaft 4 (Fig. 2) and from said shaft to the stirrer shafts 3, 3, as clearly obvious from the drawings. The main purpose of the invention of course is to separate the fines 15 from the coarse sands, the object sought being to keep the fines afloat in the pulp in the sorting chamber and cause them to move toward the overflow edge *e* of the wall *b*, and at the same time cause the coarse 20 sands to be dropped and advanced toward the tail drum 12 and the scraper blades 20 of the conveyer, said scrapers pushing the sands upward along the inclined bottom *a* and causing their discharge over the upper 25 edge of said inclined bottom into the launder 21. To effect this separation due regard must be had for the intensity and character of the agitation brought about by the revolving blades 16. The degree of 30 their pitch to the rotation plane will determine the character of current and degree of agitation, and likewise the path of advance of the coarse sands. Depending on the degree and direction of that pitch we 35 may produce an upward current or downward current; or, by turning the blades into the plane of rotation as shown in Fig. 8 (in contradistinction to the angular disposition shown in Fig. 6), we may produce 40 mere agitation without any defined upward or downward current. The adjustability of the pitch of the blades to the plane of rotation is an important feature in the present invention as it enables me 45 to adjust the agitation to the character of the pulp operated on and thereby secure effective separation of the fines from the coarse sands. In the present embodiment of the invention the fines are prevented from 50 taking the wrong direction by the deflecting aprons or diaphragms 22, which, together with the belt 11 (barring clearances of course) form an effective barrier against any tendency on the part of the fines to flow 55 toward the conveyer. In fact the aprons and belt quite well segregate the sorting compartment C from the rest of the tank 1. The coarse sands of course are caused to advance at all times toward the lower end of 60 the conveyer belt where they are picked up by the scrapers 20 and pushed along the incline *a* into the launder 21 which returns the sands to the mill (not shown) for further grinding. By shifting the belt B to 65 the proper steps of the step pulleys P, P',

any desired speed may be imparted to the stirrer shafts 3, 3. The blades 16 may of course be set to such a pitch and the speed of rotation of the stirrer shafts be so increased as to cause a portion of the coarse 70 sands to be carried away with the fines over the overflow edge *e*. If the agitation is moderate a larger volume of sands will settle than would be the case where the agitation was violent. Again, the pulleys P, P', may 75 be changed so that any desired relation of speeds between the belt conveyer and stirrer shafts may be obtained, thereby permitting the speed of the belt to be increased in the event of a settling of large quantities of 80 coarse sands. Obviously the classifier is not restricted in its application to the treatment of ores, but may be used on any material capable of classification. The apparatus may be changed in many details 85 without a departure from the nature or spirit of my invention. Features shown but not alluded to are well known in the art and a description thereof is here unnecessary. The term "belt" as used herein is 90 not to be restricted to an imperforate endless member as shown but is to be understood as including any endless member imperforate or open and made of any material whatsoever to which suitable rakes or 95 scrapers such as 20 or their equivalents may be attached.

Having described my invention what I claim is:

1. A classifier of the character described 100 comprising a tank having a bottom sorting compartment or basin provided with an overflow, and an inclined portion leading above the pulp line in said basin, means extending below the pulp line to a point between said inclined portion and overflow for feeding a charge of pulp to the basin, a belt conveyer in said tank having one end dipping below the pulp line and the opposite end terminating at a point above the pulp 105 line, agitating devices in the basin positioned below the pulp feed between the point of overflow and the adjacent end of the conveyer, and means for receiving the sands discharged from the conveyer. 110

2. A classifier of the character described 115 comprising a tank having a bottom sorting basin provided with an overflow, and an inclined portion leading above the pulp line in the basin, means extending below the pulp line to a point between said inclined portion and overflow for feeding a charge of pulp to the basin, a belt conveyer having one end dipping below the pulp line and the opposite end terminating at a point above the pulp 120 line, agitating devices positioned below the pulp feed between the point of overflow and the adjacent end of the conveyer, means for imparting a rotary sweep to said agitating devices about an axis through the pulp line, 125 130

and means for adjusting the angularity of said devices to the plane of rotation thereof about the axis aforesaid.

3. A classifier of the character described comprising a tank provided with a sorting chamber having an overflow, the tank having an upwardly inclined extension or portion leading from said sorting chamber, a belt conveyer in said extension having a lower terminal in the sorting chamber and operating to conduct the coarse sands therefrom to a point above and beyond the sorting chamber, a rotary stirrer shaft in the sorting chamber between the point of overflow thereof and the adjacent end of the conveyer, pulp-feeding means discharging below the pulp line at a point between the stirrer shaft and inclined portion of the tank, agitating blades on the shaft, sweeping in proximity to the adjacent terminal of the conveyer, and means for maintaining the blades at any desired pitch or angle to the plane of rotation thereof about the axis of the stirrer shaft.
- 25 4. In a classifier of the character described, a tank provided with a sorting compartment having an overflow, and with an inclined extension leading therefrom to a point above the pulp line in said compartment, an endless conveyer disposed in the tank and dipping at one end below the pulp line in the sorting compartment, the sides of the conveyer being spaced a suitable distance from the side walls of the tank, an agitating device in the sorting compartment in-

terposed between the point of overflow and the adjacent end of the conveyer, and suitable aprons or diaphragms spanning the spaces between the tank walls and the sides of the conveyer to offset any tendency of the fines to flow in a direction away from the overflow and toward the conveyer.

5. In a classifier of the character described, a suitable tank provided with a sorting compartment having an overflow, an endless conveyer dipping with one end below the pulp line in the compartment, a drum in the compartment for the support of the conveyer, the sides of the conveyer being spaced from the adjacent walls of the tank, scrapers disposed across the conveyer and projecting beyond the sides thereof, suitable aprons spanning the spaces between the tank walls and the side edges of the conveyer but clearing said edges and positioned slightly below the path of travel of the scrapers and clearing said scrapers, the said aprons being disposed in the general plane of travel of the upper lap of the conveyer and extending to the pulp line at the top, the lower portions dipping below the pulp line and being curved to conform to the curvature of the drum periphery, and an agitating device in the sorting compartment.

In testimony whereof I affix my signature, in presence of two witnesses.

FRANK E. MARCY.
